FOOT STOOL

Guy Scruci, 603 W. Main St., Carnegie, Pa.

Filed Mar. 30, 1959, Ser. No. 55,251

Term of patent 3½ years

(Cl. D15—8)

Fig.1.

Fig.2.

Fig.3.

Fig. 4.

Fig. 5.

FIG. 1 is a front perspective view of an adjustable foot stool showing my new design;

FIG. 2 is a rear, perspective view thereof,

FIG. 3 is a rear, perspective view thereof taken from a different angle and showing a different adjusted position,

FIG. 4 is an end view of the open end as viewed from the right of FIG. 3; and

FIG. 5 is a side view of the stool when in closed position.

I claim:

The ornamental design for a foot stool, substantially as shown.
